UNITED STATES PATENT OFFICE.

EDWIN F. BEUGLER, OF BUFFALO, NEW YORK, ASSIGNOR TO E. & B. HOLMES MACHINERY COMPANY, OF BUFFALO, NEW YORK, A CORPORATION OF NEW YORK.

HEADING HOLDER FOR BARREL-MAKING MACHINES.

Application filed February 15, 1923. Serial No. 619,253.

To all whom it may concern:

Be it known that I, EDWIN F. BEUGLER, a citizen of the United States, residing in Buffalo, in the county of Erie and State of New York, have invented new and useful Improvements in Heading Holders for Barrel-Making Machines, of which the following is a specification.

This invention relates to a pneumatic holder or gripper for use in handling articles such as barrel heads while taking them one at a time from a supply stack and introducing the same successively into the ends of barrels preparatory to securing the heads in the barrels, which operation is generally known as "heading up" in the cooperage art.

The object of this invention is to produce a holder for the heading of barrels and similar articles which is simple in construction, reliable and efficient in operation and capable of being readily operated manually with ease and facility.

In the accompanying drawings:

Figure 1 is a side elevation of my improved holder for heading up machines showing a barrel head supported thereby preparatory to introducing the same between the ends of the staves at one end of the barrel. Figure 2 is a top plan view of the same with the barrel head and staves omitted. Figure 3 is a bottom plan view thereof, partly broken away. Figure 4 is a horizontal section taken on line 4—4, Fig. 6. Figure 5 is a fragmentary vertical section on the line 5—5, Fig. 3. Figure 6 is a vertical longitudinal section, on an enlarged scale, of the holder, showing the same holding a barrel head within the croze of the staves, the section being taken on line 6—6, Fig. 2. Figure 7 is a horizontal section taken on line 7—7, Fig. 6. Figures 8 and 9 are horizontal sections taken on line 8—9, Fig. 6, looking upwardly and downwardly, respectively. Figure 10 is a sectional view of the holder similar to Fig. 6, but showing the position of the parts when no heading is being held. Figure 11 is a fragmentary vertical section taken at right angles to Fig. 10 and in line 11—11 of the same.

Similar characters of reference refer to like parts throughout the several views.

When using the holder, the same is oper-

ated so that it successively grasps a barrel head 15 which may be made in one piece or in sections, a plurality of such heads being stacked in a pile and fed one at a time from the bottom of the pile by a heading feeder, so that the holder can grasp each head on its upper side—preparatory to inserting the same into the barrel intended to receive the same.

My improved barrel head holder comprises generally a lower pneumatic gripper adapted to engage with the top of a barrel head and to become attached thereto by vacuum air pressure, a suction head adapted to be connected and disconnected with said gripper by a valve mechanism and an exhaust or suction pipe which carries the suction head.

The exhaust or suction pipe 16 is preferably arranged horizontally and so mounted that the same can rise and fall and also move horizontally back and forth between the feeder which supplies the barrel heads from a stack and the barrel holder which supports the previously assembled barrel staves 14 for receiving the heading. At its rear end the exhaust pipe is connected with an air exhausting device of any suitable character so as to create an upward suction of air through the gripper and suction head.

The pneumatic gripper comprises a gripper head having a horizontal top plate 17 provided at its margin with a depending annular flange or rim 18, both of which are preferably formed integrally of sheet metal and form a gripping chamber which opens downwardly. On its inner side the flange 18 is provided with a gripping ring 19 of metal, the lower edge of which has serrations 20 so that when the same engages the top of a barrel head 15 it will obtain a sufficiently firm hold thereon to compel the head to turn about a vertical axis and thereby facilitate the entrance of the chamfered edge 12 of the head into the croze 13 on the inner sides of the staves.

A substantially air tight joint is produced between the marginal part of the gripper and the head by means of a flexible sealing flap or gasket 21 preferably of downwardly flaring form which is arranged on the underside of the plate 17 near its edge and secured at its upper edge by clamping rings 22, 23 and bolts 24 to this plate 17.

while its lower edge when free projects below the serrations 20 but is deflected upwardly in line with the same by engagement with the upper side of the barrel head as the latter is engaged by the gripper. The descent of the gripper relatively to the barrel staves is limited by stops 25 arranged on the marginal part of the gripper head and adapted to engage with the upper edges of the barrel staves when the barrel head is in line with the croze of the staves. Rocking and oscillating of the gripper head so as to work the edge of the barrel head into the croze, if the parts fit close, is effected by means of suitable handles 26 arranged on the upper side of the gripper head.

On its front end the suction pipe has mounted thereon the suction head 27 containing the suction chamber 28 which communicates on its side with the suction pipe while its open underside is adapted to communicate with the chamber within the gripper head. In order to permit of rocking the gripper head on the suction head for working the barrel head into the croze of the staves a universal connection is provided between the same which preferably has the form of a gimbal joint and is constructed as follows:

29 represents an inner gimbal ring arranged around the open lower end of the suction head and pivotally connected therewith so as to be capable of turning about a horizontal axis relatively thereto by two horizontal pivot pins 30 arranged on diametrically opposite sides of the vertical axis of this ring and each passing radially through one part of this ring and a lug 31 depending from the adjacent edge portion of the suction head, this pin being preferably provided at its outer end with a head 32 bearing against the outer side of this ring and the inner end of the same being provided with a cotter pin 33 which retains the same in said lug 31.

Surrounding the inner gimbal ring is an outer gimbal 34 which is preferably of greater width and projects above and below the inner ring and is pivotally connected with the same by two outer pivot pins 35 arranged on diametrically opposite sides of these rings and at right angles to the pivot pins 30 and each passing radially through corresponding openings therein so that the outer and inner gimbal rings can turn about the horizontal axis of the pins 35 in a plane at right angles to the plane in which the inner gimbal ring turns relatively to the suction head. The pivot pins 35 are confined in the gimbal rings by cotter pins 36 passing through the same adjacent to the inner side of the inner gimbal ring and the outer side of the outer gimbal ring, as best shown in Fig 6.

Means are provided for detachably con-

necting the gripper head with the outer gimbal ring which means are preferably so constructed as to permit the gripper head to be turned about its vertical axis for working the barrel head into the croze or chine of the barrel staves and also to permit of readily removing the gripper head so that a larger or smaller gripper head can be substituted to suit the diameter of the barrels which are being headed. For this purpose the outer gimbal ring is provided at its lower edge with a depending rim 37 which engages with the upper side of the plate 17 of the gripper head and is provided externally with an upwardly facing annular shoulder 38, and a coupling ring 39 is provided which surrounds the rim 37 and has an upper inwardly projecting flange 40 engaging with the shoulder 38 and lower laterally projecting lugs 41 of hook shape which receive bolts 42 whereby this coupling ring is detachably connected with the plate of the gripper head, as shown in Figs. 1, 2, 6 and 10. By means of this construction the gripper head is compelled to rock with the outer gimbal ring, but can turn about its own upright axis independently thereof, and by loosening the bolts 42, the same may be withdrawn from the coupling ring lugs 41 for replacing the respective gripper head with one of a different size to fit the diameter of the barrels to be headed.

The rotary movement of the gripper head relatively to the suction head is preferably limited so that the operating handles will not become out of place and for this purpose the upper side of the coupling ring 39 is provided with two stop lugs 43, 44, which are spaced apart circumferentially and are adapted to engage opposite sides of the outer end of one of the outer pivot pins 35 which are sufficiently long for this purpose, as shown in Figs. 2, 4 and 6.

A practically air tight joint is maintained between the suction head and the gripper head by a sealing ring 70 of rubber or similar flexible material which surrounds the suction head and rests with its inner edge portion upon an upwardly facing annular shoulder 45 on the lower part of the suction head while the outer marginal portion of this sealing ring engages with the upper edge of the outer gimbal ring. The inward suction of air due to the exhausting effect produced in the suction or exhaust pipe causes the sealing ring 70 to be tightly drawn against the shoulder 45 and the outer gimbal ring and thus concentrate the suction effect on the barrel head which is held by the gripper head, and still permit the gripper to be rocked for working the barrel head into the croze of the staves.

Communication between the interior of the suction head and the interior of the gripper head is effected through a central

opening 46 in the gripper head plate 17 and a valve mechanism which is constructed as follows:

47 is a valve plate extending across the space within the outer gimbal ring below the inner gimbal ring and preferably formed integral therewith, said plate being provided with a central guide opening 48 and a plurality of valve openings or ports 49 arranged in an annular row around said central opening. Below the valve plate the outer gimbal ring is provided with an annular rabbet 50 the upper side of which forms a downwardly facing shoulder which is flush with the underside of this valve plate and forms a valve seat therewith. Engaging its upper side with the valve seat on this valve plate and rabbet is a rotary valve 51 of disk shape provided with an annular row of openings or ports 52 which are adapted upon turning the valve disk to either register with the openings in the valve plate for opening the valve, as shown in Fig. 6, or not to register with the same for closing this valve, as shown in Figs. 10 and 11. The valve disk, when closed, is drawn against its seat by the suction of the air through the exhaust pipe, but when it is open it rests with its underside against the top of the gripper plate around the opening 46 in the latter, said plate and rabbet in the outer gimbal ring together forming a guide way in which the valve rotates and is supported at its edge. In its center the valve disk is provided with a vertically extending opening 54 which is square or flat sided in cross section and which receives a correspondingly shaped coupling head 53 which is mounted on the lower end of a valve operating rod or stem 55. The latter is arranged vertically within the gripper and suction heads and passes with its upper part through a guide opening 56 in the top of the suction head and with its lower part through the central openings in the valve plate and disk and terminates with its lower end normally below the lower edge of the gripper head, as shown in Figs. 10 and 11. The coupling head 53 is preferably constructed in the form of a nut which is secured to the lower part of the operating rod 55 by means of a screw joint and also by a pin 57 passing through the nut and rod.

60 By means of this joint between the valve disk and operating rod, these two members are compelled to turn together but the operating rod is free to move lengthwise relatively to the valve disk for a purpose which will presently appear. Above the suction head the valve operating rod has fixed thereon a handle 58 which is grasped by the operator for manipulating the valve and this handle is adapted when in its

lowered position to be held against turning in the direction for opening the valve, this being preferably accomplished by locking lugs 59 arranged on the lower end of the valve handle 58 and co-operating with locking lugs 60 arranged on the upper side of the suction head, as shown in Fig. 10. Means are provided which tend constantly to turn the operating rod and associated parts in the direction for opening the air valve and also hold the operating rod yieldingly in its depressed position. In their preferred form these means comprise a helical spring 61 surrounding the operating rod within the suction head and secured at its upper end to an anchor lug 62 on the upper part of the suction head while its lower end is fastened to a screw 63 which secures a collar 64 to the operating rod within the suction head.

70 In the inoperative condition of the heading holder the valve operating rod is turned so that the coupling head thereon turns the air valve into its closed position for cutting off the air suction through the gripper head, during which movement the spring 61 is wound up and the tension upon the same is increased, and at the same time, the operating rod is depressed and its handle interlocked with the suction head so as to hold the air valve in its closed position, as shown in Fig. 10. Upon lowering the holder toward a barrel head which is to be transported or pushing such a head upward against the holder, the movement of the gripper head and barrel head one toward the other causes the barrel head to engage the lower end of the valve operating rod and to push the latter upward relatively to the gripper and suction head until the barrel head is engaged by the serrated edge of the gripper head and the sealing ring of the gripper head has been deflected and formed a tight joint between the barrel head and the gripper head. During the last part of the upward movement of the valve operating rod by engagement with the barrel head, the handle of the operating rod is unlocked from the suction head which permits the valve spring to instantly turn the valve rod and the air valve coupled therewith into an open position, as indicated in Fig. 6, thereby permitting the exhausting effect in the exhaust pipe to be exerted on the barrel head for firmly holding the latter against the underside of the gripper head. While the barrel head is thus held by the holder the latter is moved over the place where the barrel is located and then lowered for bringing the barrel head within the staves and in line with the croze or chine therein which position is determined by the stops 25 on the gripper head engaging with the upper edges of the barrel staves. After the barrel head has been thus lowered between the barrel

staves the latter are drawn inwardly by suitable means for causing them to contract and engage the croze therein with the chamfered edge of the barrel head, preparatory to receiving a hoop 65. The operator then turns the valve into its closed position by means of the handle 58 so as to cut off the air suction from the gripper and the instant this occurs the hold of the gripper on the barrel 10 is released and the holder can be raised independently of the barrel head while the latter is left within the barrel staves. As the holder is raised off the barrel head the operator depresses the handle 58 so as to interlock the same with the suction head and hold the valve in its closed position, preparatory to picking up the next barrel head and inserting the same within the staves of a barrel in the manner described.

20 The rotary movement of the air valve is preferably limited in both directions so that the same will come to a stop in its fully opened and its fully closed position for which purpose the valve is preferably provided on diametrically opposite sides of its periphery with stop lugs 66 each of which is adapted to engage with a closing stop 67 or an opening stop 68 which stops are arranged in the rabbet of the coupling 25 ring and suitably spaced apart to permit the valve to effect the requisite oscillating movement to either turn on the air suction or cut the same off.

30 In order to prevent the air valve from becoming detached from the valve plate when the top plate of the gripper head is removed from the coupling ring upon changing from one side of the gripper head to another, each of the opening stops 68 of the outer gimbal ring is provided with a beveled or undercut 35 face 69 and the corresponding side of the stop lug 66 engaging therewith has a similarly undercut base 71 so that when these corresponding pairs of undercut surfaces 40 engage with each other, the same interlock in the manner of hooks as shown in Figs. 3 and 5, which effectually sustains the valve plate in its elevated position under the rotary pressure of the valve spring and prevents the valve disk from dropping out of 45 place when the gripper head is temporarily removed.

50 This apparatus is very efficient in operation and permits of transferring barrel heads to barrel staves for assembling the same expeditiously and with a minimum expenditure of labor and power. Furthermore the several parts are not liable to wear unduly or get out of order and the same are 55 so constructed that they can be quickly and easily dismembered and assembled for adapting the holder for gripping different sizes of barrel heads and fitting them into correspondingly arranged barrel staves.

I claim as my invention:

1. A pneumatic gripper comprising a gripper head adapted to engage an article, a suction head adapted to be connected with an air exhausting device, and a universal coupling connecting said gripper head and suction head including two gimbal rings which are pivotally connected with each other on one diametrical line and one of said rings being pivotally connected with one of said heads on a diametrical line at right angles to the first mentioned diametrical line and the other ring being connected with the other head.

2. A pneumatic gripper comprising a gripper head adapted to engage an article, a suction head adapted to be connected with an air exhausting device, and a universal coupling connecting said gripper head and suction head including two gimbal rings which are arranged one within the other and which are pivotally connected with each other on one diametrical line and one of said rings being pivotally connected with one of said heads on a diametrical line at right angles to the first mentioned diametrical line and the other ring being connected with the other head.

3. A pneumatic gripper comprising a gripper head adapted to engage an article, a suction head adapted to be connected with an air exhausting device, and a universal coupling connecting said gripper head and suction head including an inner gimbal ring pivotally connected on diametrically opposite sides by radial pivots with said suction head, and an outer gimbal ring surrounding the inner gimbal ring and pivotally connected with the same on diametrically opposite sides by radial pivots arranged at right angles to the first mentioned pivots and also connected with said gripper head.

4. A pneumatic gripper comprising a gripper head adapted to engage an article, a suction head adapted to be connected with an air exhausting device, a universal coupling connecting said gripper head and suction head including two gimbal rings which are pivotally connected with each other and on one diametrical line and one of said rings being pivotally connected with one of said heads on a diametrical line at right angles to the first mentioned diametrical line and the other ring being connected with the other head, and a flexible closure extending from said suction head across said universal coupling.

5. A pneumatic gripper comprising a gripper head adapted to engage an article, a suction head adapted to be connected with an air exhausting device, a universal coupling connecting said gripper head and suction head including an inner gimbal ring pivotally connected by radial pivots with

5 said suction head, and an outer gimbal ring pivotally connected with said inner ring by radial pivots arranged at right angles to the first mentioned pivots and also connected with said gripper head, and a flexible closure extending from said suction head across said universal coupling.

6. A pneumatic gripper comprising a gripper head adapted to engage an article, 10 a suction head adapted to be connected with an air exhausting device, a universal coupling connecting said gripper head and suction head including an inner gimbal ring pivotally connected by radial pivots with said suction head, and an outer gimbal ring pivotally connected with said inner ring by radial pivots arranged at right angles to the first mentioned pivots and also connected with said gripper head, said suction 15 head having an upwardly facing external shoulder and said outer gimbal ring extending above the inner gimbal ring, and a flexible ring resting at its inner and outer edges on said shoulder and upper edge of said 20 outer gimbal ring, respectively.

7. A pneumatic gripper comprising a gripper head adapted to engage an article, a suction head adapted to be connected with an air exhausting device, a universal coupling connecting said gripper head and suction head including an inner gimbal ring pivotally connected by radial pivots with said suction head, and an outer gimbal ring pivotally connected with said inner ring by 30 radial pivots arranged at right angles to the first mentioned pivots, and means for detachably connecting said outer gimbal ring with said gripper head.

8. A pneumatic gripper comprising a gripper head adapted to engage an article, 40 a suction head adapted to be connected with an air exhausting device, a universal coupling connecting said gripper head and suction head including an inner gimbal ring pivotally connected by radial pivots with said suction head, and an outer gimbal ring pivotally connected with said inner ring by radial pivots arranged at right angles to the first mentioned pivots, and means for detachably connecting said outer gimbal ring with said gripper head.

9. A pneumatic gripper comprising a gripper head adapted to engage an article, a suction head adapted to be connected with an air exhausting device, a universal coupling connecting said gripper head and suction head including an inner gimbal ring pivotally connected by radial pivots with said suction head, and an outer gimbal ring pivotally connected with said inner ring by 60 radial pivots arranged at right angles to the 65 outer gimbal ring, and outwardly projecting lugs each of which is hook-shaped, and bolts passing through said hook shaped lugs and said gripper head.

first mentioned pivots, and means for detachably connecting said outer gimbal ring with said gripper head comprising a coupling ring having an inwardly projecting flange which overhangs said outer gimbal ring and outwardly projecting lugs each of which is hook-shaped, and bolts passing through said hook shaped lugs and said gripper head.

10. A pneumatic gripper comprising a gripper head adapted to engage an article, a suction head adapted to be connected with an air exhausting device, a universal coupling connecting said gripper head and suction head including an inner gimbal ring pivotally connected by radial pivots with said suction head, and an outer gimbal ring pivotally connected with said inner ring by radial pivots arranged at right angles to the first mentioned pivots, and means for detachably connecting said outer gimbal ring with said gripper head comprising a coupling ring having an inwardly projecting flange which overhangs said outer gimbal ring and outwardly projecting lugs connected with 80 said gripper head, and said outer gimbal ring and coupling ring being provided with co-operating stops for limiting the rotary movement of said gripper head relatively to said suction head.

11. A pneumatic gripper comprising a gripper head, a suction head adapted to be connected with an air exhausting device, and a valve for controlling the flow of air from said gripper head to said suction head comprising a valve plate having air ports, a rotary valve having ports adapted to move into and out of register with the ports in said plate, for opening and closing said valve, a spring tending to turn said valve disk in the direction for opening said valve, and locking means for holding said valve in its closed position.

12. A pneumatic gripper comprising a gripper head, a suction head adapted to be connected with an air exhausting device, and a valve for controlling the flow of air from said gripper head to said suction head comprising a valve plate having air ports, a rotary valve having ports adapted to move into and out of register with the ports in said plate for opening and closing said valve, a spring tending to turn said valve disk in the direction for opening said valve, and locking means for holding said valve in its closed position and which are adapted to be unlocked by engagement with an article.

13. A pneumatic gripper comprising a gripper head, a suction head adapted to be connected with an air exhausting device, 125 and a valve for controlling the flow of air from said gripper head to said suction head comprising a valve plate having air ports, a rotary valve having ports adapted to move into and out of register with the ports in 130
